UNITED STATES PATENT OFFICE.

CHARLES H. TRUE, OF PHOENIXVILLE, PENNSYLVANIA, ASSIGNOR TO THE RAILWAY MATERIALS COMPANY, OF CHICAGO, ILLINOIS, A CORPORATION OF ILLINOIS.

Brake-Shoe.

1,114,941.

Specification of Letters Patent.

Patented Oct. 27, 1914.

Application filed September 6, 1912. Serial No. 718,868.

To all whom it may concern:

Be it known that I, CHARLES H. TRUE, a citizen of the United States, residing at Phoenixville, in the county of Chester and State of Pennsylvania, have invented certain new and useful Improvements in Brake-Shoes, of which the following is a specification.

This invention relates to railway brake shoes of the type commonly known as "reinforced" shoes and its object is to provide a tough ductile metal attaching lug and secure it to the shoe body so that it will not become separated therefrom even if the body is cracked or fractured.

A further object of the invention is to permanently lock the ductile metal attaching lug to the reinforcing member in a secure manner and to provide means for properly positioning the lug on the plate.

The invention embodies certain novel features of construction which will be understood by reference to the following description when considered in connection with the accompanying drawings illustrating one preferred embodiment thereof.

On the drawings—Figure 1 is a plan view showing the reinforcing plate and lug embodying my invention, the shoe body being indicated in broken lines; Fig. 2 is a longitudinal sectional view through the shoe shown in Fig. 1; Fig. 3 is a bottom view of the reinforcing plate with the attaching lug secured thereto; and Fig. 4 is a perspective view of my improved attaching lug.

Referring to the drawings it will be observed that 6 indicates the body of the brake shoe which is preferably made of cast iron in any approved shape with or without inserts of any suitable character. A reinforcing plate 7 is disposed at or adjacent to the back of the shoe body, said plate being of any well known or desired contour having, if preferred, beveled edges 8 and notches 9, or other indentations or recesses to permit the entrance of the metal of the shoe body for the purpose of forming a locking engagement between the body and the plate. The plate is also shown as provided with longitudinal and transverse slots 10 and 11, respectively, into which the metal of the shoe body is permitted to flow. The end lugs 12 and the guide lugs 13 are also formed by the body metal which flows up around

the sides and ends of the plate and through the openings 10.

The plate 7 is provided on each side of the center with a pair of slots 14, preferably open-ended and parallelly disposed and spaced apart the requisite distance to receive the ends of the attaching lug. This lug, designated generally by 15, preferably consists of a metal strip or strap stamped and bent to the desired shape to fit the brake head as illustrated in the drawings. From Fig. 4 it will be observed that the lug comprises a body portion 16 which extends transversely of the shoe and is provided at each end with a pair of downwardly projecting legs 17, the spacing between the pairs of legs being sufficient to accommodate an attaching key by means of which the shoe is attached to a brake head in the usual manner. The material at the inner edges of the legs is cut away, as shown, to form the shoulders 18 which rest upon the upper face of the plate 7 at the inner ends of the slots, the extremities of the legs below the shoulders being, therefore, narrower than the portions above the shoulders so that these extremities may be inserted through the slots 14 to lie beneath the plate in the body of the shoe. After the legs have been inserted through the slots the ends are bent longitudinally of the shoe to lie against the lower face of the plate 7 and thereby lock the lug and plate together. It will be observed that the bent ends of the lug 15 lock the lug to the plate while the shoulders 18 retain the lug at the requisite height above the plate and engagement between the inner ends of the slots and the inner edges of the legs serves to prevent displacement of the lug laterally of the shoe.

The lug and the plate are preferably assembled and locked together in the manner above described and are then placed in the mold with suitable inserts, if desired, and the body of the shoe cast thereon. The lug is securely locked to the plate and the plate is securely embedded in the body, so that the lug will not become separated from the plate in service and the plate will remain united with the body even if the latter is cracked or fractured. It will be understood that the broad flat faces of the legs 17 as well as the top of the lug, herein referred to as the body portion 16, will engage the brake head and as the lug is made of

ductile metal there will be little, if any, wear upon the head in service.

It is believed that my invention will be understood from the foregoing without further description and, it will be obvious to those skilled in the art, that various changes in the size, shape and proportion of the various parts may be resorted to without departing from the scope of the invention as set forth in the appended claim.

I claim:

A brake shoe comprising a reinforcing back provided with a pair of transversely extending centrally disposed slots at each side, an attaching lug secured to said back consisting of a strip of suitable material

bent transversely of the back at each side of the center of said strip and cut away between the ends and the bends to provide a flat top, a pair of downwardly extending legs, said legs being disposed through the slots in the back, the portions of the said legs in the slots being cut away to provide shoulders engaging the upper face of the reinforcing back and the extremities of said legs being bent up in contact with the under face of said back, and a body cast on said back.

CHARLES H. TRUE.
